FECUNDITY CALENDAR

Gerrit Hendrik Heetbrink, Haarlem, and Coenraad Van Emde Boas, Amsterdam, Netherlands

Application February 23, 1954, Serial No. 411,974

3 Claims. (Cl. 235—86)

The present invention relates to an indicator for determining the period during which a woman is capable of conceiving, which indicator is based on the division of a cycle into three periods viz. the first infertile period, the fertile period and the second infertile period.

A known indicator of this type is based on the "Ogino-Knaus" method. This method starts from the division of the ripening cycle into three terms viz. the first infertile period, the fertile period and the second infertile period.

In said method use is made, for example, of the following formulae:

- I First day of the fertile period = L. M. + ($n_{\min.} - 19$)
 II Last day of the fertile period = L. M. + ($n_{\max.} - 12$)

in which L. M. represents the date of the latest menstruation, $n_{\min.}$ represents the number of days of the shorter cycle and $n_{\max.}$ the number of days of the longer cycle.

We have now found that the above formulae do not hold good for all cases. According to the supplementary method discovered by Dr. Van Emde Boas a few days are still added to the last day of the fertile period after the determination of the fertile and infertile periods according to the "Ogino-Knaus" method and the number of said additional days may vary with the variable duration of the so-called longer cycle.

In the case of a longer cycle of 26 days, for example, 4 days are added; 3 days are added when the longer cycle covers 27 or 28 days; to a cycle of 29 or 30 days 2 days are added; to a cycle of 31 or 32 days 1 day is added, etc.

A condition for the application of the supplementary Van Emde Boas method is that first the duration of 12 successive cycles be determined experimentally to thus obtain the values of $n_{\max.}$ and $n_{\min.}$. These are the periods from one menstruation to the next menstruation. The first day of a subsequent menstruation is reckoned to belong to the following cycle.

The object of this invention is to adapt an indicator of the type described to the improved van Emde Boas method.

For this purpose the indicator according to the invention comprises a date scale admitting of being set for any given date as the latest menstruation date and covering at least another 35 days beyond said date, a scale for indicating a shorter cycle, a scale for indicating a longer cycle, said indicator furthermore comprising a window for setting a date, said window and said date scale being relatively movable, adjustable means for indicating the end of the first infertile period and adjustable means for indicating the beginning of the second infertile period, said two means being adjustable by means of the first and the second scale respectively, the arrangement being such that while the date scale is freely movable relative to the remainder of the indicator the adjusted indicating means admit of being arrested relative to the date setting window.

A practical embodiment of said indicator which meets the above conditions and which so indicates the fertile period that it can be easily read therefrom may be char-

2

acterized according to the invention by a date band longitudinally movable over a support, a stationary zero index for said date band, two cursors adjustable over said support and said date band and a plurality of numbers provided on said support in connection with the variable duration of a menstruation period, by means of which numbers the one cursor is set for the shorter and the other cursor for the longer menstruation period observed, the numbers provided on the support being arranged in two separate groups of numbers relating to variable values of the longer and the shorter menstruation period respectively, said cursors each being provided with an opaque portion covering said date band.

Of the one group of numbers relating to the variable values of $n_{\min.}$, each $n_{\min.}$ number may be added to the graduation $n_{\min.} - 19$ of a regular scale having the zero index for its zero point.

Of the other group of numbers relating to the variable values of $n_{\max.}$, each $n_{\max.}$ number may be added to the graduation $n_{\max.} - 12 + t$ of the same regular scale having the zero index for its zero point, t having an experimentally determined value which is variable in dependence on the value of $n_{\max.}$.

If the cursors are now so adjusted that the opaque portion of the one cursor commences at the graduation to which $n_{\min.}$ has been added and that the opaque portion of the other cursor ends at the graduation to which $n_{\max.}$ has been added, which opaque portions overlap more or less, a portion of the date band will be covered, which portion corresponds with the fertile period.

By arranging the two groups of numbers in two separate series it is possible to provide said groups with an appropriate legend which has an illuminating effect. It is also possible now to give each group a distinctive colour.

The indicator described is very simple and also easily operable.

The drawing illustrates the invention and in the drawing:

Figure 1 shows a vertical cross section of an indicator according to the invention;

Figure 2 shows a vertical section normal to the one according to Fig. 1;

Fig. 3 shows a view thereof as seen looking to the circumference of the date band;

Fig. 4 in a side view illustrates the provision of the numbers relating to the menstruation cycles along the edge of a side face of the indicator.

The indicator according to Figures 1—4 comprises a cylindrical, flat box divided into symmetrical halves in its circumferential direction. Said two halves are connected with each other by a central screw bolt 1. The reference numeral 2 designates a spool which has its ends rotatably mounted in holes in the discs 3 and 4 forming the bottoms of the box halves. The one end 5 of the spool projecting beyond the box constitutes a knob by means of which the spool can be rotated. A second spool 6 is mounted for rotation in the same manner as the first spool and is located diametrically opposite the first spool relative to the screw bolt 1. Said spool may be rotated by turning the projecting end 7. To each spool one end of a date band 8 is secured, which date band is wound a number of times on each spool and which leaves the box through an opening 9 in the circumference thereof and which on either side of said opening surrounds the circumference of the box in a closed loop. On the circumference of the box a window 10 is mounted and two covering cursors 11 and 12 are so mounted on the box as to be slidable in the circumferential direction thereof. The date band passes beneath the window 10 and the covering cursors. Said band rests in a circumferential groove 13.

On the date band the dates of 15 successive months

are provided. On the date band shown the first number represents the day and the second number the month. The first twelve months are those of a normal year, the last three months, viz. January, February, and March are provided because February 29 has been included for a leap year. In order to avoid mistakes the background on which said three months appear may have a colour other than the colour used for the background of the twelve months of a normal year.

On the, or on each of, the flat bottoms along the circumference thereof numbers relating to the menstruation cycles are arranged (vide Figure 4). In elucidation thereof the following may serve:

If the latest fertile day is calculated by means of the formula $L. M. + n_{\max.} - 12$ this gives for a longer cycle of $n_{\max.} = 26$ days:

$$L. M. + (26 - 12) = L. M. + 14$$

For 27 days this is $L. M. + 15$ etc. and for 36 days $L. M. + 24$. To these numbers the safety additions according to Van Emde Boas are still to be added. These safety additions are for a longer cycle of

26 days: 4 days
27 days: 3 days
28 days: 3 days
29 days: 2 days
30 days: 2 days
31 and more days: 1 day

If these safety additions are taken into account in making the first-named calculation the latest fertile day in the case of a longer cycle of

$$\begin{aligned} 26 \text{ days will be: } & L. M. + 14 + 4 = L. M. + 18 \\ 27 \text{ days will be: } & L. M. + 15 + 3 = L. M. + 18 \text{ etc.} \\ 36 \text{ days will be: } & L. M. + 24 + 1 = L. M. + 25 \text{ etc.} \end{aligned}$$

It makes no difference, therefore, whether the longer cycle amounts to 26 or 27 days. The latest fertile day is in both cases the same, which is because in the case of 26 days the uncertainty requires an addition of four days and in the case of 27 days an addition of only three days. The same applies to 28 and 29 and also to 30 and 31 days.

The result is that on the side of the box (as from the window) are counted out: 18 days (26,27); 19 days (28,29); 20 days (30,31); 21 days (32); 22 days (33), etc.

Thus the settings are obtained for the covering cursor belonging to the longer cycle, so to the value of $n_{\max.}$. These settings are indicated by the notches 14 shown in Figure 4 at the right hand bottom side, which notches are provided with indications of the values belonging to $n_{\max.}$. It should be noted that not all of the notches actually used in practice have been shown, but only enough to illustrate their position on the device.

For the cursor belonging to the shorter cycle, so to the value of $n_{\min.}$ one may proceed in a similar manner.

These settings for said last-named cursor are indicated at the top of Figure 4 as notches 15 provided with indications of the values belonging to $n_{\min.}$. Likewise, not all of these notches are shown. Also, in practice, these notches are placed on the other side of the device. When using the indicator the date band is moved so far by means of the knobs 5 and 7 that the date of the latest menstruation L. M. appears in the window 10 (zero index).

The covering cursors 12 and 11 set respectively for the values of $n_{\max.}$ and $n_{\min.}$ holding good for the case under consideration will then cover the days of the fertile

period on the date band. In doing so the covering cursors are placed with the leading edges of their opaque portions at the notches against which the relative value of n is marked.

5 The operation of the fecundity calendar according to Figs. 1-4 is as follows:

The annular slide bearing the indication "shortest cycle" is displaced so that it is adjusted in accordance with the numeral (e. g. 28) of the shortest cycle. The annular slide bearing the indication "longest cycle" is then adjusted in accordance with the numeral (e. g. 32) of the longest cycle. By means of the knobs 5, 7 the date band is adjusted so that the indication 1-1 can be read through the window 10. Arrows (not shown) on the side wall 3 indicate the direction of rotation.

If the adjustment has been effected correctly (cycle 28-32) the following dates can be read successively: 1-1 (Jan. 1); 2-1; 3-1; 4-1; 5-1; 6-1; 7-1; 8-1; 9-1. Then follows an opaque portion whereupon the date scale 10 becomes visible again at 22-1; 23-1, etc. The correct ending of this scale cannot be indicated exactly since it depends on the date at which the following menstruation begins.

In the window 10 the date of the first day of the last menstruation of the woman is adjusted. All of the dates visible are the dates on which said woman is infertile. All of the not visible dates are fertile days.

We claim:

1. A fecundity calendar for determining the power of conception of women and being based on the division of a cycle into the first infertile period, the fertile period and the second infertile period, and comprising a cylindrical box-shaped casing, a date band mounted within said casing and adapted to be passed over the circumferential wall of said casing, a stationary zero-index on the periphery of said casing over said band, two cursors adjustable over the circumferential wall of the casing and said band and a plurality of numbers provided on said casing corresponding to the variable duration of a menstruation period, by means of which numbers the one cursor is set for the shorter and the other cursor for the longer menstruation period observed, the numbers provided on the casing being arranged in two separate groups of numbers corresponding to variable values of the longer and the shorter menstruation period respectively, said cursors each having an opaque portion covering said date band.

2. A fecundity calendar as claimed in claim 1, comprising a first shaft mounted for rotation in an upper part of the casing, a second shaft mounted for rotation in a lower part of the casing, one end of the date band being attached to said first shaft, said band being wound a number of times on said shaft, the casing having an opening in its circumferential wall through which the band is lead around the outside of said wall and back into the casing and is wound a number of times on said second shaft to which its other end is attached, the band thus forming a closed loop surrounding the casing, and means for rotating said shafts.

3. A fecundity calendar as claimed in claim 1, in which the two separate groups of numbers are placed along the circumferential edge of a side wall of the casing and the cursors or slides are mounted so as to be slidable or adjustable over one another.
